CLAIM

The ornamental design for a lid with a handle, as shown and described.

DESCRIPTION

FIG. 1 is a perspective view of a lid with handle, showing my new design, in a position of use with an exemplary tumbler, with a cap in a closed position;

FIG. 2 is a perspective view thereof, with the cap in an open position;

FIG. 3 is a front view of the lid with handle, with the exemplary tumbler removed for clarity of disclosure, and with the cap in a closed position;

FIG. 4 is a rear view thereof;

FIG. 5 is a right side view thereof;

FIG. 6 is a left side view thereof;

FIG. 7 is a top plan view thereof; and,

FIG. 8 is a bottom view thereof.

The surface shading and contour lines shown in the drawings represent the three dimensional character and contour

(Continued)

of the article, and are not intended to illustrate material, surface ornamentation or surface decoration.

The broken lines are shown for the purpose of illustrating environmental subject matter of an exemplary tumbler, and parts of the article, none of which form part of the claim.

1 Claim, 6 Drawing Sheets
